Primary Examiner — Susan E Krakower*(74) Attorney, Agent, or Firm* — Kyle Fletcher**CLAIM**

I claim the ornamental design for the rolling push up device, as shown and described.

DESCRIPTION

FIG. 1 is a side view of the rolling push up device.
FIG. 2 is a front view of the claimed design.
FIG. 3 is a rear view of the claimed design.
FIG. 4 is a top view of the claimed design.
FIG. 5 is a bottom view of the claimed design; and,
FIG. 6 is a perspective view of the claimed design.
